(57) CLAIM

The ornamental design for a lid, as shown and described.

DESCRIPTION

FIG. 1 is a front perspective view of a lid showing my design;

FIG. 2 is a rear perspective view of the lid of FIG. 1;

FIG. 3 is a front view of the lid of FIG. 1;

FIG. 4 is a rear view of the lid of FIG. 1;

FIG. 5 is a side view of the lid of FIG. 1, the opposite side being the same; and,

FIG. 6 is a top view of the lid of FIG. 1.

The broken line showing in FIGS. 1 through 5 is for illustrative purposes only and forms no part of the claimed design.

1 Claim, 6 Drawing Sheets

FIG. 1

FIG. 2

FIG. 3

FIG. 4

FIG. 5

FIG. 6
